UNITED STATES PATENT OFFICE.

ABRAHAM I. LEWIS, OF NEWARK, NEW JERSEY.

CIGAR-BAND.

1,178,245.

Specification of Letters Patent.

Patented Apr. 4, 1916.

Application filed November 17, 1914. Serial No. 872,533.

To all whom it may concern:

Be it known that I, ABRAHAM I. LEWIS, a citizen of the United States, residing at Newark, in the county of Essex and State of New Jersey, have invented new and useful Improvements in Cigar-Bands, of which the following is a specification.

This invention relates to a band which is essentially adapted for encircling the body 10 of a cigar.

The fundamental object of the invention is to provide the band with a coupon having inscriptions representing the value of the coupon.

15 The novel features of the invention are more fully described in the following specification and claims and illustrated in the accompanying drawing in which:—

Figure 1 represents a rear view of a cigar 20 showing the method of attaching the band. Fig. 2 is a similar view showing the band detached.

In the drawing the letter *a* designates a band which is preferably made of paper. 25 This band includes a coupon *b* forming one end of the band, while the central portion *c* represents the face of the band. One end of the band is provided with an adhesive surface *d* whereby the end can be joined as 30 indicated in Fig. 1 to the face of the coupon. When it is desired to attach the band to a cigar the adhesive end is moistened and brought over on top of the coupon so that the band will somewhat tightly span the circumference of the cigar and thus be retained 35 in place. This method of joining the band to the top of the coupon prevents any of the mucilage from getting into contact with the wrapper of the cigar and sticking of the band to the cigar is thereby avoided. The configuration of the coupon is practically 40 oval shaped as indicated and it has perforated parts *e* whereby it is united to the band. When desired the coupon can be 45 readily detached from the band by tearing along the perforations. The face of the coupon is provided with inscriptions denoting that it is a profit sharing voucher and a numeral representing the value of the 50 coupon. A number of these coupons have a fixed value and when detached and sent to the manufacturer of the cigars the sender

will be entitled to a premium depending on the number of coupons. The face of the member *c* can be provided with replica denoting the trade name of the cigar, and the band can have the name of the manufacturer of the cigar printed thereon. When the cigar is packed in a box the coupon will not be exposed inasmuch as the cigar is arranged 60 in the box with the face of the coupon downward.

I claim:—

1. A band adapted to encircle a cigar, consisting of a narrow strip of paper having an 65 enlarged central portion and provided with an enlarged end having thereon inscriptions to represent a profit-sharing coupon.

2. A band adapted to encircle a cigar, consisting of a strip of paper having replica 70 denoting the name of a cigar, and a detachable coupon formed by an enlarged portion of the band with inscriptions representing the profit sharing value of the coupon.

3. A band adapted to encircle a cigar, consisting of a strip of paper having replica 75 denoting the trade name of a cigar, and a detachable coupon forming an enlarged end of the band with inscriptions representing the profit sharing value of the coupon. 80

4. A band adapted to encircle a cigar, consisting of a strip of paper having an enlarged central portion with replica denoting the trade name of a cigar, a detachable oval shaped coupon located at the rear end 85 portion of the band with inscriptions thereon representing the profit sharing value of the coupon, and an adhesive end for attachment to the face of the coupon.

5. A cigar band comprising a narrow strip 90 of paper enlarged intermediate its ends to receive the name of a cigar and having a transversely enlarged portion upon the end of the strip to represent a profit sharing coupon, said second enlarged portion at the 95 end of the strip being separable from the strip by a line of perforations.

In testimony whereof I have hereunto set my hand in the presence of two subscribing witnesses.

ABRAHAM I. LEWIS.
